UNITED STATES PATENT OFFICE.

JOHN MATKOVCIK, OF MICHEL, BRITISH COLUMBIA, CANADA.

RAIL CHAIR AND FASTENER.

1,044,215.

Specification of Letters Patent. Patented Nov. 12, 1912.

Application filed June 8, 1912. Serial No. 702,525.

To all whom it may concern:

Be it known that I, JOHN MATKOVCIK, citizen of the United States of America, and resident of Michel, Province of British Columbia, Dominion of Canada, have invented certain new and useful Improvements in Rail Chairs and Fasteners, of which the following is a specification, reference being had therein to the accompanying drawings.

10 This invention relates to a rail chair and fastener, and the objects of my invention are, first, to provide a novel chair for supporting a rail upon a wooden tie whereby the tie will not be worn by a movement of 15 the rail; second, to furnish the rail chair with novel fasteners for positively supporting the base flanges of a rail upon the chair; third, to provide a rail chair and fastener that can be used in connection with the present type of wooden tie and quickly arranged to support the present type of rail, and fourth, to provide a rail chair and fastener consisting of comparatively few parts that are durable and inexpensive to manufacture.

I attain the above objects by a mechanical construction that will be hereinafter specifically described and then claimed, and reference will now be had to the drawing, 30 wherein:—

Figure 1 is a longitudinal sectional view of a portion of a tie provided with the rail chair and fastener; Fig. 2 is a plan of the same, and Fig. 3 is a perspective view of 35 a fastener member.

A rail chair in accordance with this invention comprises a tie plate 1 that is provided with a plurality of depending prongs 2 adapted to engage in the top of a wooden 40 tie 3 and anchor said tie plate relatively to said tie. The plate 1, adjacent to the outer edge thereof, has a longitudinal outer fastener 4 extending from one end of said tie plate to the opposite end thereof, said fastener being in the form of an overhanging flange that engages the outer base flange 5 of a rail 6 mounted upon the tie plate 1. Contiguous to the outer fastener 4 there are 45 openings 7 providing clearance for spikes 8 that are driven in the tie 3 to hold the outer end of the tie plate 1.

The edge of the tie plate 1 has a longitudinal inwardly projecting curved brace 9 that is provided with vertical openings 10 alining with openings 11 in the tie plate 1, 55 said openings accommodating spikes 12 employed for securing the inner end of the tie plate 1 upon the tie 3.

The tie plate 1, adjacent to the brace 9, has a longitudinal seat 13 extending from one edge of the tie plate to the opposite edge thereof. The seat 13 accommodates a rail fastener 14 that has a curved inwardly projecting flange 15 overhanging the inner base flange 16 of the rail 6. The flange 15 of the inner rail fastener engages the inner wall of the brace 9 and the flange 15 is notched, as at 17 to provide clearance for the spikes 10.

After the rail 6 is placed upon the tie plate 1, the inner fastener is driven into position and then the spikes 12 driven into the tie 3 to lock the inner rail fastener relatively to the tie plate 1.

What I claim is:—

A rail chair and fastener comprising a tie plate for supporting the base flange of a rail, a longitudinally extending outer fastener integral with said plate at a point removed from the outer longitudinal edge thereof and adapted to overlap the base flange of a rail, a curved brace integral with the inner longitudinal edge of said plate and provided with vertical openings, said plate adjacent to said brace cut away to form a longitudinal seat, an inner rail fastener mounted in said seat and engaging the upper and lower faces of the base flange of a rail, said curved brace overlapping said inner fastener, said inner fastener having notches alining with said openings, said tie plate having that portion projecting from the outer fastener provided with openings, spikes extending through the last mentioned openings and spikes extending through the openings of the brace and the notches of the inner fastener.

In testimony whereof I affix my signature in the presence of two witnesses.

JOHN MATKOVCIK.
